SHOE SOLE

Norman E. Bovay, Naugatuck, Conn., assignor to United States Rubber Company, New York, N. Y., a corporation of New Jersey

Application September 3, 1953, Serial No. 26,695

Term of patent 7 years

(Cl. D7—5)

To all whom it may concern:

Be it known that I, Norman E. Bovay, a citizen of the United States, residing at Naugatuck, in the county of New Haven and State of Connecticut, have invented a new, original, and ornamental Design for a Shoe Sole, of which the following is a specification, reference being had to the accompanying drawing, forming a part thereof.

The figure is a bottom perspective view of a shoe sole showing my new design.

I claim:

The ornamental design for a shoe sole, as shown.
